Des. 206,089
Patented Oct. 25, 1966

206,089

PLASTIC PANEL

Irwin W. Spar, 309 W. Brookdale Place, and Barbara J. Durand, 3240 Santa Maria Ave., both of Fullerton, Calif.

Filed Sept. 8, 1965, Ser. No. 86,905

Term of patent 3½ years

(Cl. D54—2)

FIG. 5

FIG. 1 is a fragmentary front elevation view of a plastic panel formed by a plurality of interconnected component blocks having alternate outwardly curved textured surfaces and alternate inwardly curved surfaces which are smooth;

FIG. 2 is a perspective view of a component block used to form the panel of FIG. 1;

FIG. 3 is a plan view of the component block of FIG. 2;

FIG. 4 is a fragmentary rear elevation view of the plastic panel of FIG. 1; and,

FIG. 5 is a cross-sectional view of the component block of FIG. 2.

The panel is of indeterminate exterior dimensions and the design repeats as indicated.

We claim:

The ornamental design for a plastic panel, substantially as shown and described.
